CLAIM

The ornamental design for a scuba tank carrier, as shown and described.

DESCRIPTION

FIG. 1 is a perspective view of the scuba tank carrier, showing the new design;

FIG. 2 is a bottom plan view thereof; the opposing top view being a mirror image;

FIG. 3 is a front elevational view thereof; the back view being a mirror image;

FIG. 4 is a side view thereof; the opposing side being a mirror image; and,

FIG. 5 is an alternative perspective view thereof, illustrating use of the device.

The broken line showing of the scuba tank carrier is for illustrative purposes only and forms no part of the claimed design.
